UNITED STATES PATENT OFFICE.

HOUGHTON SAWYER, OF PIEDMONT, CALIFORNIA.

OBSERVATION OPENING FOR DOORS.

Application filed October 7, 1925. Serial No. 60,983.

This invention relates to observation fittings which may be applied to doors and the like to permit observation of the surroundings exteriorly of the door without opening the door or disclosing the observer.

It is the principal object of the present invention to generally improve devices of the character referred to by providing a simple and inexpensive observation fitting which may be easily and quickly applied to a door or the like and by the use of which a person interiorly of the door may obtain an extended view of the surroundings exteriorly of the door without being observed.

In carrying out the invention into practice I provide a fitting composed of telescoping parts which may be inserted and clamped in an opening in a door or the like. An opening is formed through the fitting which converges from the exterior side of the door to the interior side thereof. This opening permits a maximum range of observation of the surroundings exteriorly of the door to be obtained without disclosing the observer.

One form which the invention may assume is exemplified in the following description and illustrated by way of example in the accompanying drawings, in which:

Fig. 1 is a central horizontal section through an observation fitting embodying the preferred form of my invention.

Fig. 2 is an elevation of the exterior end of the device.

Fig. 3 is an elevation of the interior end of the fitting, disclosing the open position of the shutter in dotted lines.

Referring more particularly to the accompanying drawings, 10 indicates a door or the like through which a circular opening 11 is bored or otherwise formed. Mounted within this opening and extending transversely through the door is an observation fitting 12. This fitting is composed of an outer section 14 and an inner section 15 which are formed with telescoping sleeves 16 adapted to threadedly connect at their contiguous ends. The sections are formed with circumscribing flanges 17 at their outer ends which abut against opposite surfaces of the door when the sleeves 16 are threadedly connected to clamp the sections of the fitting into position within the opening 11.

The outer section 14 of the fitting is formed with an inwardly projecting frusto-

conical portion 18 which extends within and through the sleeves 16 to a point contiguous to an opening 19 formed in the face plate 20 of the inner section 15 of the fitting. It is seen that the frusto-conical portion of the outer fitting provides an outwardly divergent opening through the fitting so as to give an extended range of vision in all directions with a very small opening for the eye. Therefore, a person located interiorly of the door may fully observe the surroundings immediately exteriorly of the door without being observed.

In order to close the opening 20 when desired, a shutter 21 is pivoted to the inner section 15 and is provided with a knob 22 by which it may be swung about its pivot point to cover or uncover the opening.

In practice, the parts are constructed substantially as shown and described. A circular opening is then bored through the door or wall in the desired location and the sleeves of the two sections of the fitting are inserted in opposite ends thereof. The contiguous ends of the sleeves are then threadedly connected and the sections are drawn together until their circumscribing flanges tightly abut against the surfaces of the door.

It is seen that by this construction, the fitting may be applied to doors of different thicknesses without altering the construction of the fitting. The threaded portions of the sleeves 16 permit them to telescope until the circumscribing flanges 17 thereof tightly abut against opposite surfaces of the door.

In the present instance I have struck lug 23 out from the face plate 20 of the inner section and in a position whereby it will be engaged by the cover plate or shutter 21. By grasping the knob of the shutter plate and tending to move it in a direction causing it to abut against the lug, a firm purchase may be had on the inner section by which it may be revolved to thread the sections together. While revolving the inner section, the outer section is held stationary.

From the foregoing it is obvious that the device may be easily applied to doors in a very inexpensive manner without the necessity of the use of screws or other fastening elements to secure the device in place. By providing the device with an opening which converges from the exterior to the interior surfaces of the door, a person interiorly of the door may obtain an extended range of vision of the surroundings immediately ex-

teriorly of the door without being observed. While I have shown the preferred form of my invention, it is to be understood that various changes in its construction may be made by those skilled in the art without departing from the spirit of the invention.

Having thus described my invention, what I claim and desire to secure by Letters Patent is:

- 10 1. An observation fitting for doors comprising a pair of substantially cylindrical members adapted to be inserted into opposite ends of an opening formed transversely through a door, the adjacent ends of said members being adapted to be telescopically connected to adapt the fitting to the thickness of the door, a face plate on one member, an inwardly projecting frusto-conical tube on the other member converging toward the face plate and having its inner end open, said face plate having an opening formed therethrough in alignment with the conical tube.
- 15 2. An observation fitting for doors comprising a pair of substantially cylindrical members adapted to be inserted into opposite ends of an opening formed transversely through a door, the adjacent ends of said members being adapted to threadedly connect whereby they will telescope to connect the members and adapt the fitting to the thickness of the door, a face plate on one member, an inwardly projecting frusto-conical tube on the other member converging toward the face plate and having its inner end open, said face plate having an opening formed therethrough in alignment with the conical tube.
- 20 3. An observation fitting for doors comprising a pair of substantially cylindrical members adapted to be inserted into opposite ends of an opening formed transversely through a door, the adjacent ends of said members being adapted to be telescopically connected to adapt the fitting to the thickness of the door, a face plate on one member, an inwardly projecting frusto-conical tube on the other member converging toward the face plate and having its inner end open, said face plate having an opening formed therethrough in alignment with the conical tube.
- 25 4. An observation fitting for doors comprising a pair of substantially cylindrical members adapted to be inserted into opposite ends of an opening formed transversely through a door, a face plate on one member, an inwardly projecting frusto-conical tube on the other member converging toward the face plate and having its inner end open, said face plate having an opening formed therethrough in alignment with the conical tube.

open, said face plate having an opening formed therethrough in alignment with the conical tube, and a shutter pivoted to the face plate and adapted to cover said opening.

3. An observation fitting for doors comprising a pair of substantially cylindrical members adapted to be inserted into opposite ends of an opening formed transversely through a door, the adjacent ends of said members being adapted to threadedly connect whereby they will telescope to connect the members and adapt the fitting to the thickness of the door, a face plate on one member, an inwardly projecting frusto-conical tube on the other member converging toward the face plate and having its inner end open, said face plate having an opening formed therethrough in alignment with the conical tube, and a shutter pivoted to the face plate and adapted to cover said opening, a lug struck from the face plate and engageable by said shutter to facilitate the connecting of said cylindrical members.

4. An observation fitting for doors comprising a pair of substantially cylindrical members adapted to be inserted into opposite ends of an opening formed transversely through a door, a face plate on one member, an inwardly projecting frusto-conical tube on the other member converging toward the face plate and having its inner end open and contiguous to the face plate, said face plate having an opening formed therethrough in alignment with the conical tube.

HOUGHTON SAWYER.
